A. W. REILING

SAFE

Filed Aug. 20, 1921

INVENTOR.

A. W. Reiling

BY *Elwin M. Ulrey*
KIO ATTORNEY.

UNITED STATES PATENT OFFICE.

AUGUST W. REILING, OF FORT WAYNE, INDIANA.

SAFE.

Application filed August 20, 1921. Serial No. 493,883.

To all whom it may concern:

Be it known that I, AUGUST W. REILING, a citizen of the United States, residing at Fort Wayne, in the county of Allen and State of Indiana, have invented new and useful Improvements in Safes, of which the following is a specification.

The invention relates to safes and particularly to safes for the display of money or valuable articles.

The object of the invention is to provide a safe or a system of safes with means by which money or other valuable articles may be displayed or placed conveniently for use and instantly covered up in the safe or safes where they are inaccessible for selected periods of time.

The invention consists in a safe having a normally exposed receptacle for valuable articles, means operative exteriorly of the safe for closing the receptacle and a time lock on the safe set in action by the operation of the receptacle closure means for securing the closed condition of the receptacle for selected periods of time.

In the accompanying drawings I have illustrated an embodiment of the invention in which Figure 1 is a plan view of a device constructed in accordance with the invention; Fig. 2 a front elevational view of the same, the door being open; Fig. 3 an end view of the same broken away; Fig. 4 a fractional, sectional view of the opposite end of the same, the receptacle being closed, and Fig. 5 a view of a plurality of safes equipped with the invention.

Referring to the drawings, 10 is a case of usual or convenient type having drawers 11 therein for the storage of money or valuable articles, and 12 is a door hinged on the front side of the case and having suitable locking bolts 13 connected by a plate 14 for simultaneous reciprocation by a revoluble handle 15 having a suitable connection to the plate for causing the bolts to move into engagement with the door frame 16 of the case. Springs 17 are suitably connected to the bolts and engage the door and tend to move the bolts into locking position. Hence the door can not be closed unless the handle is turned to withdraw the bolts so that the door will take its seat.

A time lock mechanism 18 of usual construction is secured to the rear side of the door. The spring driven dials 18 of the mechanism carry laterally projecting pins

19 adapted to abut the fingers 20 depending from a longitudinally movable bar 21 and move the bar toward the left (Fig. 2). A tumbler 22 is pivotally mounted at 23 above the bar 21, the lower end of one arm of the tumbler being in front of a pin 24 projecting outwardly from the bar so that when the bar is reciprocated by the dials the tumbler will swing to elevate its opposite arm 25 out of the path of an arm 26 secured to the plate 14. In Fig. 2 the tumbler is in its down position and arm 26 abuts or will abut the end of the tumbler if the handle 15 is turned, thus locking the bolts against all movement. When the bar 21 is reciprocated and the tumbler 22 is rocked to elevate its arm 25, a pin 27 on said arm engages the hook shaped arm 28 of a pawl 29 pivotally mounted at 30 by which the tumbler is supported in elevated position, and during such position of the tumbler the bolts 13 may be thrown at will.

In order that the clock mechanism shall be held from operating I pivot a latch 31 below the bar 21, one arm of which latch is adapted to engage a rack 32 formed on the bar 21. A pin 33 projecting from a tripping bar 34 engages the other arm of the latch and prevents rotation of the latch by the bar 21 under the influence of the dials 18.

The tripping bar 34 is longitudinally slideable on pins 35 projecting from the door and extending through the slots 36 in the bar. A pin 37 projects from the bar 34 and is adapted to abut and rock the pawl 29 for releasing the tumbler 22 from its engagement on the hook, whereupon the tumbler drops down to the locking position shown in Fig. 2. At the same time the pin 33 rocks the latch 31 and releases the bar 21 and the clock mechanism begins to run to reciprocate the bar 21 and rock the tumbler 22 out of the path of the arm 26 and cause it to engage on the hook pawl 29.

The clock mechanism may be set for any selected period of time of operation so that a selected period must elapse before the bolts 13 may be moved to unlock the safe.

The tripping bar 34 carries a pin 38 which, when the door is closed, is engaged by an arm 39 projecting forwardly from a link 40 which extends upwardly through the bottom of the case. The lower end of the link is pivoted to a suitably mounted foot pedal 41, by the depression of which pedal the link is reciprocated upwardly. The up-

per end of the link is pivotally connected to one end of a latch 42, the opposite end of the latch being adapted to bear on the surface of a cylindrical shell 43 and to engage 5 in an opening or recess 44 therein for locking the shell in open position. The ends of the shell are closed and carry suitable bearings by which the shell is revolubly supported on a shaft 45 fixed at its opposite ends to the 10 sides of the case. An open top receptacle 46 is secured on the shaft within the cylinder, and at a suitable point, preferably diametrically opposite opening 44, an opening or slot 47 is formed in the cylinder corresponding 15 in size to the top of the receptacle and which, when the latch 42 locks the cylinder, will register with the top of the receptacle. An opening 48 is formed in the top of the case and over the receptacle to afford access 20 to or visibility of the contents of the receptacle.

A spring opposed latch 49 is pivotally mounted adjacent the opposite end of the cylinder and is adapted to engage in an 25 opening or recess 50 therein when the cylinder is rotated by weight 51 attached at a suitable point to the cylinder. The latch 49 rides on the surface of the cylinder and the opening 50 is so located that the cylinder 30 upon the release of the latch 42 will have rotated sufficiently to cause its shell to entirely cover the open top of the receptacle before the latch 49 is thrown in by its spring as shown in Fig. 4. A handle 52 is attached 35 to the cylinder for convenience in restoring the cylinder to the open position upon the release by hand of the latch 49. It will be noted that both the latches 42 and 49 are entirely within the case, hence access there- 40 to is cut off so long as the door is closed.

The operation is readily understood. It is intended that normally the door shall be closed, the clock mechanism set for operation in a selected period of time, the tumbler operating bar 21 locked by the latch 31, the tumbler 22 held up by the pawl 29 and the cylinder in the open position. In this condition of the safe the locking bolts may be thrown at will and the door opened and 45 closed to gain access to the drawers 11. The user, as for example a bank teller, will place such amount of money in the receptacle as he may choose and pay out of it and deposit in it money received. He may keep 50 his surplus cash in the drawers. In an emergency, as in the case of a "hold up", all that he has to do is to depress the foot pedal. The upward movement of the link 40 releases the latch 42, the cylinder in- 55stantly swings over the receptacle and is locked by the latch 49, and the arm 39 lifts the tripping bar 34 which in turn releases the latch 31 from the tumbler actuating bar and also releases the hook pawl 29 from the tumbler 22 which tumbler instantly drops 60 65

down and prevents all movement of the arm 26 and of the bolts until the selected period of time for which the clock mechanism has been set has expired and the time bar 21 has been moved by the dials to again 70 elevate the stop. Upon releasing the pedal the link drops down and the latch 42 contacts with the cylinder. Also the tripping bar drops down and the latch 31 and the pawl 29 are free to perform their respective functions. 75 When the tumbler has again engaged on the pawl 29 the locking bolts on the door may be thrown to open the door. After opening the door the time-lock mechanism is again reset and the latch 49 is released and the cylinder rotated in proper direction until latch 42 again locks it in the open position. 80 The clock mechanism could be set to open, say, in one hour. The safe and its contents including the contents of the receptacle are 85 therefore securely locked up for an hour and access to the safe can not be had during that period of time. The operation of the latches and pawls and cylinder is practically simultaneous and instantaneous, hence a 90 maximum of safety is achieved.

A battery of the safes may be connected for simultaneous operation, all that is necessary is to suitably mount a rod 52^a (Fig. 95 5) and connect the link 40 of each safe to it, each safe also having a foot pedal 41 connected to the rod. By depressing any one of the pedals the rod is elevated to elevate all the links and close the receptacles and lock all the safes simultaneously. The rod could be extended to an adjoining room where a pedal 53 would operate it and accomplish the same results.

What I claim is:

1. A case having an opening in one of its walls, a receptacle accessible through the opening, movable means within the case to close the opening, means to control the closing movement of the movable means having an operating connection exteriorly of the case, a door on the case, locking bolts on the door, means to lock the bolts against movement, means normally supporting the latter means in inactive position, a time lock mechanism, means to lock the said mechanism against operation and means adapted to be operatively connected to the said controlling means when the door is closed, to simultaneously release the time lock mechanism and the engagement of the bolt locking means on its support whereupon the bolt locking means moves into locking position and the clock mechanism at the expiration of a selected period of time restores the said bolt locking means onto its support.

2. A case having an opening in one of its walls, a receptacle accessible through the opening, movable means within the case to close the opening, means to control the closing movement of the movable means having

- an operating connection exteriorly of the case, a door on the case, locking bolts on the door, a tumbler to lock the bolts against withdrawal, means normally supporting the 5 tumbler in inactive position, a time-lock mechanism for moving the tumbler into engagement with its support, means to lock the time-lock mechanism against operation, and means adapted to connect to the said controlling 10 means when the door is closed to release the clock mechanism and the tumbler from its support simultaneously whereupon the tumbler moves into operating position to lock the door bolts and the clock mechanism 15 operates for a selected period of time to restore the tumbler on its support.
3. A case having an opening in one of its walls, a door opening and a door therefor, a receptacle fixed within the case and accessible through the opening, a revoluble cylinder enclosing the receptacle and adapted to automatically close the said opening and having an opening therein normally registering with the opening in the case, a latch to lock the cylinder in its said normal position, a link pivoted to the latch for releasing the latch and extending through a wall of the case, means outside the case having connection with a link for reciprocating it and 25 means to lock the cylinder after it has closed the opening in the case.
4. A case, a door for the case, locking bolts on the door, a tumbler adapted to lock the bolts against movement, a member normally 30 supporting the tumbler in inactive position, a time-lock mechanism, a reciprocable member adapted to be driven by the clock mechanism for moving the tumbler from its locking position to its inactive position, means 35 to lock the reciprocable member against movement, a tripping member adapted to engage and release the tumbler and the latter locking means simultaneously to cause the tumbler to move into its locking position and to cause the reciprocable member under 40 the influence of the clock mechanism to restore the tumbler to its inactive position after the expiration of a selected period of time, a reciprocable member in the case adapted to be engaged by the tripping member 45 when the door is closed and means outside the safe having connection with the reciprocable member in the case for operating it.
5. In a safe, the combination with a case, 50 a receptacle fixed within the case and normally accessible through an opening in a wall of the case, means to control the said opening for cutting off access to the receptacle, a door on the case, locking bolts on the door 55 adapted to engage the case when the door is closed, means to lock the bolts against movement when in engagement with the case, a time-lock mechanism on the door adapted to release the bolt locking means at a predetermined time, means normally holding the bolt locking means inactive, means to hold the time-lock mechanism inactive and means to release both said holding means for locking the said bolts and for unlocking the same at 60 a predetermined time, said releasing means having an operating connection, when the door is closed, with the said controlling means, and means outside the case having a connection with the controlling means for 65 operating the same to cut off access to the receptacle and simultaneously operate the said releasing means.
- In witness whereof I have hereunto subscribed my name this 18th day of August, 1921.

AUGUST W. REILING
